BOAT HULL

Marcus A. Hall, Bethany, Conn., assignor to Steelcraft Boats, Incorporated, a corporation of Connecticut

Application May 21, 1945, Serial No. 594,831

12 Claims. (Cl. 9—6)

1

This invention relates to boat hulls, and more particularly to boat hulls constructed of metal, such as steel. The invention also relates more particularly to the hull structure of a boat of the speedboat type, but the invention is not limited to that particular application.

One of the objects is to provide an improved metal hull structure.

Another object is to provide a strong lightweight hull which is cheap to manufacture.

Another object is to provide a strong hull comprising, principally, plates of relatively light gauge metal, the plates being of a minimum number.

Another object is to provide an improved hull structure in which the hull is formed of plates welded together by continuous welds, the joint formation being such as to give the hull great strength.

In the accompanying drawings:

Fig. 1 is a side elevation of a boat hull embodying my improvements;

Fig. 2 is a top plan view of the same;

Figs. 3, 4, 5, 6, 7 and 8 are respectively sections on lines 3—3, 4—4, 5—5, 6—6, 7—7 and 8—8 of Fig. 1;

Fig. 9 is a transverse section of the lower part of the hull on a larger scale, taken adjacent the section line 3—3 of Fig. 1;

Fig. 10 is a similar section taken adjacent the section line 5—5;

Fig. 11 is a similar section taken adjacent the section line 6—6;

Fig. 12 is a similar section taken adjacent the section line 7—7;

Fig. 13 is an enlarged section of the chine portion of the hull taken adjacent the section line 4—4 of Fig. 1;

Fig. 14 is a similar section taken adjacent the section line 5—5;

Fig. 15 is a similar section taken along the section line 15—15 of Fig. 1;

Fig. 16 is a similar section taken adjacent the section line 7—7;

Fig. 17 is a similar section taken adjacent the section line 8—8;

Fig. 18 is a detail showing the blank for the bottom plate; and

Fig. 19 is a detail of the transom plate.

In the example selected for illustration in the drawings, the hull is one suitable for a speedboat having a length of say twenty-six feet, this dimension, however, being given only by way of example. The hull is constructed for the greater

2

part of steel plate members bent to the required shape and welded together. The hull is shown as equipped with an inboard motor, but the boat may, if desired, be driven by an outboard motor. In general, the hull is characterized by a wide and high body usual in speedboats, the body having a covered deck, and rearwardly of the deck an open cockpit. Along the sides of the cockpit in this example are continuations of the forward deck plate.

In the drawings, transverse sections of the hull are shown in Figs. 3, 4, 5, 6, 7 and 8, the first of these being taken near the stem, the second and third through the wide portion of the bow, the fourth through the forward part of the cockpit, the fifth through a narrower portion of the cockpit, and the last (Fig. 8) being taken at a point near the stern. From these, it will be seen that near the stem the hull is characterized by a high and narrow shape, generally triangular, widening out into the shape of Fig. 4, with a flattening of the bottom. In Fig. 5, the V of the bottom has further flattened, the side walls are shorter and have less angle to the vertical. In Fig. 6, the bottom is further flattened, and the side walls are further shortened. In Fig. 7 the side walls are further shortened and the angles of the side walls come up more nearly to the vertical. In Fig. 8, the angles of the side walls to the vertical are reverse angles as compared to Fig. 7.

The hull comprises essentially a deck plate 20 of metal such as steel, side plates 21, a bottom plate 22, and a transom plate 23. The plates referred to (except the transom plate) may be continuous from stem to stern, that is to say, in one piece, and it is preferred to make them in this way, although they can, if desired, be made up of sections suitably interconnected end to end as by welding. The several main plates are interconnected by means of continuous welds. It is unnecessary to employ separate rail members. It is desirable, however, to use a keel strip in the manner hereinafter described. This keel strip preferably extends from the top of the stem to a point rearwardly of the widest part of the bow, where it terminates. The keel strip is indicated in the drawings at 24. Within that part of the hull which lies rearwardly of the keel strip is a reinforcing member 25 in line with the keel strip suitably attached to the bottom plate 22 and preferably extending from the rear end of the keel strip to the transom plate 23. This reinforcing member 25 is preferably in the form of a

relatively thick metal plate having its rear end abutted against the transom plate and welded to the bottom plate and transom plate by welds such as shown at 26 in Fig. 12.

The bottom plate 22 is preferably made from a blank 22^a such as shown in Fig. 18. This blank is substantially as long as the completed hull, and it is characterized by a bifurcated forward formation such as shown in Fig. 18. In its initial flat form, it has forwardly tapering portions 27 with gradually rounded edges and forward points 28, these portions or furcations being separated by a space 29 defined by edges converging rearwardly toward a point 30. In constructing the hull, the bottom plate is bent to the shape shown in the drawings, the furcations 27 being brought into close adjacency, so that they can be welded to the keel strip 24 in the manner shown in Figs. 9, 10 and 11. The keel strip 24 preferably has a semi-round cross section, being rounded at the lower part and flat at the upper part, and the portions of the bottom plate are welded to the flat upper face, for which purpose the plate portions are provided with flanges 31. These flanges 31 lie against the upper face of the strip and have their opposing faces spaced apart at a suitable distance, and in the space between their opposing faces, welds 32 are placed, one of such welds 32 being at the edge of each plate portion. Outside welds 33 are also used, these welds 33 being located alongside the curved outer surface of the keel strip and being in locations where the flanges 31 form angles with the bodies of the respective plate portions. In the portion of the hull shown in Fig. 9, the furcations 27 are bent upwardly at a relatively steep angle. In the direction of the stern, the angle is decreased. In the preferred form, the angle goes up steeply adjacent the stem to a line such as 34 (Fig. 9) and, from this line, the steepness of the rise is increased to a slight extent. The welds 32 and 33 extend rearwardly substantially to the crotch 30 where the keel strip terminates and the inner reinforce 25 begins.

Marginal portions of the furcations 27 have a lapped relation to the side plate 21, as shown more particularly in Figs. 13 to 17 inclusive. It is preferred to have the lower parts of the side plates on the outside and the upper portions of the bottom plate on the inside, there being a substantial overlap, and continuous welds at the edges of the respective plates, each such weld connecting the edge of the respective plate to the face of the adjacent plate. The joint is formed between a portion 35 of the side plate and a portion 36 of the bottom plate, as appears in Fig. 13, for example, where the continuous edge welds referred to are indicated at 37 and 38. As will be seen from Figs. 13 to 17 inclusive, the lapped portions of the side plate and the bottom plate bear substantially the same relation to each other at different points in the length of the hull, but the joint portion has different relationship to a vertical plane at points lengthwise of the hull in the chine portion of the latter. Between the points where the sections of Figs. 13 and 14 are taken, there is little variation, the lapping portions of the plates being approximately horizontal, but, when the section line 15—15 is reached, the lapping portions have an upward inclination which is increased in the section of Fig. 16. When the section of Fig. 17 is reached, the lapping portions have a reverse angle of inclination to the vertical, as compared to Fig. 16.

It will be noted from Figs. 4, 5 and 6 that in

the body portion of the hull there is protuberance or projection to the exterior in the chine region that presents a shoulder or shelf, the structure being of a character to provide a spray rail or spray rib which causes the spray to be thrown laterally rather than upwardly. This feature is not present adjacent the stem, but the projecting rib commences somewhat forward of the section line 4—4 and gradually increases in size to a maximum. It begins to diminish in size rearwardly of the line 6—6 and disappears before the section line 7—7 is reached. On referring to Figs. 13 to 17, inclusive, it will be seen that Figs. 13 and 14 show the spray projection or rib at about its maximum extent. In Fig. 15 it is disappearing, and in Figs. 16 and 17 it has disappeared.

In the boat hull of the invention, the structure is such as to accommodate suitable interior frame members, but the present invention is not concerned with the frame members, if any, and no such members are shown in the drawings.

One of the important features of the invention is the use of a minimum number of plate members. It will appear from the foregoing that the plate members are of a minimum number and of simple form. They can be readily interconnected by continuous welds as in the example described. Another advantage arises from the fact that the structure is well suited to building by mass production methods, there being no need of great accuracy and precision in locating the edge portions of the plates for the creation of the welds. Nor is it necessary to cut the plates with extreme accuracy. It will be noted that the joint between each side plate and the bottom plate is a lap joint and that the joint between the bottom plate portion and the keel strip is also a lap joint. The amount of overlap can vary within rather wide limits without harming the strength and appearance of the structure, and in connection with each lap joint two different welds can be used, thus insuring a very strong structure. It will be seen by reference to Figs. 9, 10 and 11 that the joint between each part of the bottom plate and the keel strip is similar to the joint of Fig. 13, for example, not only because there is a lap in connection with which two welds are used, at different points, but because the keel strip provides an element in the nature of a flat surfaced plate lapping the portion of the bottom plate. The weld 33 moreover is at the edge of this element of the nature of a plate. All of the welds referred to are in locations where welds can be made readily. No joint is necessary in the bottom plate between the crotch and the transom plate.

It will be noted that the spray rail portion of the hull merges into the hull body gradually at the ends of the spray rail. In the spray rail portion of the hull the side plate has a bent portion or flange at the lower part, and the bottom plate has a bent portion or flange at its upper part, the flanges providing the portions of the respective plates which are lapped, and the flanges being of appreciable width to provide increased strength and to provide a satisfactory joint comprising edge welds, as shown, for example, in Fig. 13. The flanges, being at angles to the bodies of the respective plates, greatly increase the strength of the hull, and, moreover, provide welding areas that are remote from the rather flat plate bodies, which plate bodies might be distorted if the welds were formed directly thereon. By comparing Figs. 13, 14 and 15 it will

be seen that the lapped joint, in the different portions of the hull length where the spray rail is provided, is of the same formation and character notwithstanding the different inclinations of the side plate and bottom plate to a vertical plane, and that the lapped joint itself is at varying angles to such a plane at different points in its length. It is also noted that in this structure the weld placed at the edge of a given plate is spaced laterally from the bend in that plate and the bend in the other plate.

It is also to be noted that in the keel portion of the hull illustrated in Figs. 9, 10 and 11, the strength of the hull is increased at a result of the provision of flanges at the lower ends of the side plates. These flanges lie flatwise against the upper surface of the keel and have the same relation to it at different points in the length of the hull, as shown in Figs. 9, 10 and 11, the difference at different points in the hull length being in the angle defined between the flange and the plate body.

In the spray rail portion of the hull the flange provided on the side plate is, in general, in a laterally directed position so as to afford good support for the flange of the bottom plate which is superimposed upon it. This is a further factor increasing the strength of the hull and its weight-carrying capacity.

In one aspect of the invention the furcations at the forward portion of the bottom plate are interconnected by welding them by continuous welds to a plate member, this plate member preferably being applied externally as in the case of the keel strip shown in this example.

While only one example of the hull structure is shown in the drawings, it will be understood that the invention can take many other forms and that various modifications and changes in the details can be made without departing from the principles of the invention or the scope of the claims.

What I claim is:

1. A boat hull comprising metal plates interconnected, said hull having at the chine portions side plates and a bottom plate structure joined by lap joints, each lap joint including two edge welds of the plates, the lapping portions of each side plate and of the bottom plate being at different angles to the vertical lengthwise of the hull.

2. A boat hull comprising metal plates interconnected, said hull having at the chine portions side plates and a bottom plate structure joined by lap joints, each lap joint including two edge welds of the plates, the lapping portions of each side plate and of the bottom plate being at different angles to the vertical lengthwise of the hull, the chine portion being formed as a spray rib through a portion of the hull length.

3. A boat hull comprising metal plates interconnected, said hull having at the chine portions side plates and a bottom plate structure joined by lap joints, each lap joint including two edge welds of the plates, the lapping portions of each side plate and of the bottom plate being at different angles to the vertical lengthwise of the hull, the chine portion being formed as a spray rib through a portion of the hull length, each side plate having a lapping portion on the exterior of a portion of the bottom plate.

4. A boat hull comprising interconnected metal plates including side plates and bottom plate portions, and the hull having chine members constituted by lapping portions of the side plates

and bottom plate portions, each chine member including two welds associated with the edges of the lapping portions, the lapping portions in a portion of the hull length being disposed at angles to the bodies of their respective plates, and the angular portion on one lapping on the angular portion on the other to provide spray ribs.

5. A boat hull having at the chine portion a side plate and a bottom plate joined by a lap joint, said joint being formed between lapping portions of the side plate and bottom plate respectively at different angles to a vertical plane, said lapping portions throughout a portion of the hull length being at angles to the plates to provide a spray rib.

6. A boat hull having a side plate and a bottom plate joined by a lap joint at the chine portion of the hull, said lap joint comprising flanges formed respectively on the plates and overlapping each other and secured together by edge welds, said flanges being at different angles to a vertical plane at different points lengthwise of the hull and providing in a portion of the hull length a spray rib.

7. A boat hull having a side plate and a bottom plate joined by a lap joint at the chine portion of the hull, said lap joint comprising flanges formed respectively on the plates and overlapping each other and secured together by edge welds, said flanges being at different angles to a vertical plane at different points lengthwise of the hull and providing in a portion of the hull length a spray rib, said spray rib having ends which merge into the hull body.

8. A boat hull having a side plate and a bottom plate joined by a lap joint at the chine portion of the hull, said lap joint comprising flanges formed respectively on the plates and overlapping each other and secured together by edge welds, said flanges being at different angles to a vertical plane and at different angles to the bodies of their respective plates at different points lengthwise of the hull and providing in a portion of the hull length a spray rib, said edge welds being laterally spaced from the bends at the base portions of the flanges.

9. In a boat hull, a keel member in the nature of a plate having a flat upper surface, and a hull plate having a lower integral flange placed against the upper surface of the first plate, and two linear welds fastening the plates together, one being at the edge of each plate, the body of the second plate being at different angles to its flange at different points in the length of the hull.

10. A boat hull comprising side plate portions and bottom plate portions joined together to form chines, said plate portions having edge portions overlapping and interconnected in the bow of the hull and lying substantially in the planes of the respective bodies of said plate portions, said plate portions having approximately horizontal flanges amidships that are overlapped and interconnected and provide spray-rib portions, and the hull having astern of said spray-rib portions a joint structure between said plate portions in which the bottom plate portion is flanged and the side plate portion unflanged, the side plate portion adjacent the joint in this portion being inclined so as to be closer to the vertical than in the spray-rib portion, and the side plate portion adjacent the joint at the stern being at a reverse inclination to the vertical.

11. A boat hull having bottom plate portions and side plate portions overlapped at the chine portions of the hull, said plate portions being interconnected at each side of the hull by a weld along a lower edge provided upon the side plate portion and a weld along an upper edge provided upon the bottom plate portion, there being at each side of the hull in a part of its length a spray-rib formation formed by flanges provided upon the respective plate portions, the welds being laterally spaced from the bends by which the flanges are created.

12. A boat hull having bottom plate portions and side plate portions overlapped at the chine portions of the hull, said plate portions being interconnected at each side of the hull by a weld along a lower edge provided upon the side plate portion and a weld along an upper edge provided upon the bottom plate portion, there being at each side of the hull in a part of its length a spray-rib formation formed by flanges provided upon the respective plate portions, the welds being laterally spaced from the bends by which the flanges are created, both of said plate portions being unflanged sternwardly of the spray-rib formation, and one of said plate portions be-

ing unflanged sternwardly of the spray-rib formation.
